UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

SWITCH-CONTROLLING SYSTEM.

1,413,501.

Specification of Letters Patent. Patented Apr. 18, 1922.

Application filed December 16, 1919. Serial No. 345,194.

To all whom it may concern:

Be it known that I, FRANKLIN A. STEARN, a citizen of the United States, residing at Paterson, in the county of Passaic, State of New Jersey, have invented certain new and useful Improvements in Switch-Controlling Systems, of which the following is a full, clear, concise, and exact description.

This invention relates to telephone systems and more particularly to systems in which machine switching apparatus is employed for establishing connections.

In certain types of machine switching telephone systems it is customary to provide controlling mechanisms common to a plurality of connecting circuits for controlling the selective movement of the automatic switches in the establishment of connections. These mechanisms comprise a plurality of registers which operate, in response to the transmission of impulses from a calling transmitter or to the actuation of keys on an operator's keyboard, to take up positions corresponding to the designations of called lines. With the registers in their set positions, a series of counting relays, arranged for association with said registers, are successively operated in variable combinations to determine the amount of movement to be imparted to the selective switches which are undergoing control. The several registers, corresponding to the units, tens, hundreds, etc., places of the called numbers, are generally provided with ten controlling positions or settings, one for each of the ten numeral digits. Consequently, the counting relays cooperating with these registers are arranged to be energized in any one of ten different combinations according to the settings of the registers.

It is the object of this invention to provide, in a system of the foregoing character, a counting relay set by means of which each of the controlling registers require only a comparatively few settings to accomplish the usual control of the selective switches.

A feature of the invention relates to a set of counting relays divided into two groups, the first group being used for selections in which certain digits are concerned, both groups being used for selections in which other digits are concerned and so organized that a particular relay in each of said groups, which is always the last relay to be operated in such group, serves

to bring about the termination of the selective operation.

Other features and advantages of the invention will become more apparent from a consideration of the following description.

In the drawing, Figures 1, 2, and 3, when arranged with Figure 2, below Figure 1 and Figure 3 to the right of Figure 2, illustrate so much of a telephone system as is necessary for an understanding of the invention. Fig. 1 shows a trunk or connecting circuit incoming to an operator's position and terminating in a group selective switch. Fig. 2 shows the relay set of a controlling mechanism for controlling the operation of the selective switches such as the one shown in Fig. 1. This figure also illustrates diagrammatically a trunk-finder switch for associating the register controlling mechanism with the incoming trunk. Fig. 3 shows two sets of keys on the operator's keyboard and the corresponding registers which are positioned in accordance with the actuation of these keys.

The selective switch disclosed herein is of the well-known power-driven panel type, such as shown in the patent to Craft and Reynolds, 1,123,696, issued January 5, 1915. The construction and operation of the sequence switches used for controlling the circuits in this system are shown and described in the patent to Reynolds and Baldwin 80 1,127,808, issued February 9, 1915. The trunk-finder shown in Fig. 2, may be of any approved type such as the one shown in the patent to Lundell, 1,168,319, issued January 18, 1916. The registers used in this system, and the method in which they are variably positioned under the control of the operator's keys sets, are similar to those shown in the above mentioned patent to Lundell.

In accordance with the present invention, the counting relay set which serves to determine the selective movement of the switches in accordance with the positioning of the registers, is divided into two groups. By this expedient it is only necessary to provide the registers with five different controlling positions, each. The several registers, corresponding to the units, tens, hundreds, and so forth, places in the called line numbers, may be arranged to be set, in each of their five positions by means of two different keys in the corresponding row. That is to say, either the number 0 key or number

5 key, when depressed causes the register to be set in its zero position; either the number 1, or the number 6 key, when depressed causes the register to be set in its first position; either the number 2 or the number 7 key, when depressed causes the register to move to its second position, and so on. It will be noted that the registers are adjusted to each of their several positions by means 10 of one key which represents a digit less than 5, and by a second key which represents a digit greater than 5. If the digit concerned in a given selective operation is less than 5, a number of counting relays of the first 15 group corresponding to such digit are successively energized. When the last relay of this group is energized, this particular relay always being the one last energized in the group, the movement of the switch undergoing control is terminated. If, however, the 20 digit is greater than 5, a translating relay operates after the register has taken its position. In this case a variable number of relays of the first group, also dependent upon 25 the digit, are operated the same as for digits less than 5. When the last relay of the first group is energized, no effect is produced upon the movement of the selective switch. Instead, the counting relays of the 30 second group are all energized in succession. Upon the energization of the last relay of the second group, this relay always being the last one energized when the group is taken for use, the operation of the selective 35 switch is terminated.

A detailed description of the operation will now be given, assuming that the operator at the position shown, has been notified over an order wire by a distant operator, 40 that a call is awaiting the assignment of an idle trunk. Neither the distant operator's position nor the order wire are shown, since they are not essential to the present invention. The operator at the position shown 45 instructs the distant operator that the trunk 101, 102 is idle and assigns such trunk by the depression of an assignment key 103. The operation of this key closes a circuit including contact 104 (1) for driving sequence switch 110 out of position 1 and into position 2. In position 2 of sequence switch 110 the trunk-finder whose brushes are shown at 200, 201, is started in operation to select the assigned trunk. Upon the 50 brushes 200 and 201, making engagement with terminals 202 and 203, individual to the assigned trunk, the sequence switch 110 advances from position 2 into position 5. The circuits for initiating the hunting operation of the trunk-finder, and for the advance of the sequence switch 110 after the assigned trunk has been seized, are not shown in detail. For a complete disclosure 55 and explanation of the manner in which this operation is accomplished, reference is

made to the above mentioned patent to Lundell, No. 1,168,319.

The operator, having had the number of the desired line communicated to her by the distant operator, proceeds to set up such 70 number on her keyboard. For simplicity only two rows of keys and their corresponding registers are shown in this disclosure, though any number of rows of keys may be provided to suit the capacity of the system. 75 It will be taken for example that the first two digits of the called number are 1 and 4. Accordingly the operator depresses key 302 in the first row and key 303 in the second row. She then operates the start key 80 300 which completes parallel circuits for registers 310 and 320, these circuits including respectively the right hand armatures and contacts of relays 314 and 324. The register 310 rotates until it reaches position 85 1, at which time a circuit is closed from battery through the winding of relay 314, contact 311 (1), contact of the depressed key 302 to ground. Relay 314 becomes energized and opens the circuit of the register 90 310 causing this register to stop in position 1. The register 320 rotates until it reaches position 4, at which time a circuit is completed from battery through the winding of relay 324, contact 323 (4), contact of the 95 depressed key 303 to ground. The relay 324 energizes and opens the circuit of register 320, whereupon this register comes to rest in position 4. With both relays 314 and 324 energized, a circuit is established from battery through the winding of sender sequence switch 210, contact 211 (1), conductor 217, left-hand armatures and contacts of relays 314 and 324 to ground. The sequence switch 210 advances from position 1 into position 4. 100 In position 4 of the sender sequence switch 210 the fundamental circuit is closed for controlling the brush selective operation. This circuit may be traced from battery through the right-hand winding of relay 107, contact 117 (5), contact 116 (5), conductor 124, terminal 203, brush 201, winding of the stepping relay 204, armature and contact of relay 206, contact 205 (4), brush 200, terminal 202, conductor 125, contact 109 (5 to 6) to 105 ground. The relay 107 energizes and completes a circuit from ground through the contact 114 (2 to 17), left-hand armature and front contact of relay 107, contact 106 (5), winding of sequence switch 110 to battery and ground. Sequence switch 110 moves from position 5 into position 6. Relay 107 remains energized in position 6 of sequence switch 110 by means of a substitute path closed through its inner right-hand armature and contact and sequence switch contact 117 (3 to 10). In position 6 of sequence switch 110 a circuit is closed for the up-drive 110 power magnet 120, including contact 122 (6), front contact and left-hand armature 115

of relay 107 and contact 114. The brush shaft is moved upward, and for each conducting segment of commutator 126 engaged by brush 127, the following circuit is closed: battery through the right-hand winding, and inner right-hand armature and contact of relay 107, contact 117, contact 118, (5 $\frac{1}{2}$ to 6), commutator 126, brush 127 to ground. This direct path to ground serves to shunt the stepping relay 204 in the fundamental circuit. The stepping relay 204, which energized in series with relay 107, when the fundamental circuit was closed, completes a circuit from ground through its armature and contact, contact 213 (4), conductor 218, contact 315 of the register 310 closed in its first position, conductor 220, armature and back contact of the number 1' counting relay 221 of the first group of counting relays, winding of the number 1 relay 222, contact 215 (4) to battery and ground. Relay 222 energizes and prepares a locking circuit for itself in series with relay 221. Relay 221, however, does not energize at this time since it is shunted at the armature and contact of the stepping relay 204. When the brush 127 engages the first conducting segment of commutator 126, relay 204 deenergizes and permits relays 222 and 221 to lock up in series with each other. This locking circuit may be traced from battery through contact 215 (4), windings of relays 222 and 221, contact and armature of relay 222 to ground. When relay 204 again energizes, the circuit traced through register contact 315, and conductor 220 now leads over the armature and front contact of relay 221, conductor 223, back contact and left-hand armature of relay 214, winding of relay 207 to battery and ground. The relay 207 becomes energized in this circuit and prepares at its armature and contact a circuit for itself including parallel branches through the windings of relays 206 and 207, and contact 209 (4). Relays 206 and 208, do not energize, however, since they are shunted by the direct path to ground at the armature and contact of relay 204. As soon as relay 204 deenergizes, this shunt is removed and relays 206 and 208 lock up in series with relay 207. Relay 208 closes a circuit from ground through its contact and armature, and contact 211 (4) for driving sequence switch 210 into position 6. In passing from position 4 to position 6, contacts 215 and 209 are opened to permit the release of all counting relays that have been energized. The relay 206 opens the fundamental circuit at the sender whereby the relay 107 is permitted to deenergize as soon as the brush 127 reaches the next insulating segment of the commutator 126. Relay 107 closes a circuit from ground through contact 114 (2 to 17), left-hand armature and back contact of relay 107, contact 106 (6), winding of sequence switch 110 to battery and ground. Sequence switch 110 advances from position 6 into position 7. In position 7 the trip magnet 113 is energized in a circuit closed at contact 114 ready to trip the selected set of brushes, in the well-known manner, upon the next upward movement of the brush shaft. With sequence switches 110 and 210 in positions 7 and 6 respectively, the fundamental circuit is closed for controlling the group selecting movement of the switch. Relay 107 by energizing closes a circuit from ground through the contact 114 (2 to 17), left-hand armature and front contact of relay 107, contact 106 (7), winding of sequence switch 110 to battery and ground for moving this sequence switch into position 8. Relay 107 as before remains energized in the fundamental circuit by a substitute path closed at its inner right-hand armature and contact, and sequence switch contact 117. Up-drive magnet 120 is energized in a circuit closed through contact 122 (8), front contact and left-hand armature of relay 107, and contact 114. The switch shaft is driven upward in its group selecting movement. For each conducting segment of the group selecting commutator 129 that the brush 128 engages, the following substitute circuit is completed for the energization of relay 107; battery through the right-hand winding of relay 107, contact and inner right-hand armature of said relay, contact 117 (3 to 10), contact 118 (7 $\frac{1}{2}$ to 8), commutator 129, brush 128 to ground. This direct path to ground shunts out the stepping relay 204 in the fundamental circuit. Upon the energization of the stepping relay 204 in the fundamental circuit, a circuit is closed from ground through the armature and contact of relay 204, contact 213 (6), conductor 219, contact 326 of register 320 closed in position 4, conductor 224, armature and back contact of the number 4' counting relay 225 of the first group, winding of the number 4 counting relay 226, contact 215 (6) to battery and ground. Relay 226 energizes and as soon thereafter as the stepping relay 204 is shunted relay 225 energizes and locks up in series with relay 226. In this manner each of the three succeeding pairs of relays of the first group are energized in response to the operation of the stepping relay 204. After the relay 221 becomes energized the next energization of relay 204 closes the above described circuit for relay 207. The next deenergization of the stepping relay 204 permits the energization of relays 206 and 208. Relay 208 closes the above traced circuit for the sequence switch 210 which thereupon advances from position 6 to position 1 and relay 206 opens the fundamental circuit. As soon after the fundamental circuit is opened at the sender, as the brush 128 encounters an insulating portion of the

group selecting commutator 129, relay 107 deenergizes. Relay 107 closes a circuit from ground through the contact 114 (2 to 17), left-hand armature and back-contact of relay 107, contact 106 (8), winding of sequence switch 110 to battery to ground. Sequence switch 110 moves out of position 8 and into position 9.

In position 9 of sequence switch 110 a circuit is closed from battery through the right-hand winding of relay 107, contact 117 (9 to 9 $\frac{1}{2}$), contact 115 (9 to 9 $\frac{1}{2}$) to ground. Relay 107 closes a circuit from ground through contact 114 (2 to 17), left-hand armature and front contact of relay 107, contact 106 (9), winding of sequence switch 110 to battery and ground for driving said sequence switch into position 10. If the first trunk in the group, upon the terminals 20 of which the brushes are resting, is busy, relay 107 is maintained energized in position 10 of sequence switch 110 in the following circuit: battery through the left-hand winding of relay 107, contact 108 (9 to 10), contact and outer right-hand armature of relay 107, upper left-hand contact 123 (2 to 11), lower contact 123 (9 to 16 $\frac{1}{2}$), brush 130 to ground at the busy terminal 131. Up-drive magnet 120 is, therefore, energized in a circuit from battery through the winding of said magnet, contact 122 (10), front contact and left-hand armature of relay 107, contact 114 to ground. The brush shaft moves upward until an idle trunk is reached at 35 which time relay 107 deenergizes and opens the circuit of the power magnet 120 causing the brushes to come to rest. Relay 107 by deenergizing closes a circuit from ground through contact 114, left-hand armature and back contact of relay 107, contact 106 (10), winding of sequence switch 110 to battery and ground. Sequence switch 110 advances into position 13 which is the talking position of the switch. The selected trunk is made 45 busy by the application of ground on terminal 131 over a circuit including brush 130, lower contact 123 (9 to 16 $\frac{1}{2}$) and upper right-hand contact 123 (11 to 18).

In passing from position 6 to position 1 50 the sender sequence switch closes a circuit from ground through contact 227 (7 to 8), windings of key release magnets 317 and 328 in parallel to battery and ground. These magnets, which serve to maintain the operated keys in the depressed position, cause the release of said keys when energized.

It has thus been shown how the first 55 group of the counting relay set controls the selective operation of the switches when the digits involved in such selection are less than the digit 5. An example will now be taken in which one of the selective operations of the switches involves a digit greater than the digit 5. For this purpose it 60 will be assumed that it is desired to operate

the switch shown in Fig. 1 in accordance with the designation 18. Accordingly the operator depresses number 1 key 302 in the first row and number 8 key 304 in the second row. Key 302 causes the register 70 310 to be set in position 1 as above described. Key 304, which, it will be observed, is connected to register contact 322 in position 3, causes the register 320 to be set in position 3. In the manner already explained the 75 setting of register 310 in position 1 determines that the counting relays of the first group only are successively energized to control the movement of the switch to select the proper set of brushes. The sender sequence switch 210 then advances to position 6, and the fundamental circuit is closed to control the selection of a group of trunks corresponding to the depressed key in the second row of keys. Since the key 304 represents a digit greater than 5, the following circuit is completed in position 6 of the sender sequence switch 210: battery through the winding of translating relay 214, contact 212 (6), conductor 228, right-hand contact of key 304 to ground. The translating relay 214, which operates in response to the actuation of any key representing a digit greater than 5, determines that after the proper number of relays of the first group 80 have been energized, all the counting relays of the second group must be energized in succession before the fundamental circuit is severed to terminate the group selecting movement of the switch. With relay 204 85 energized in the fundamental circuit a circuit is completed from ground through the armature and contact of said relay, contact 213, (6), conductor 219, contact 326 (3), conductor 229, armature and back contact 90 of relay 230, winding of relay 231, contact 215 (6) to battery and ground. Relays 231 and 230 energize and lock up in series, as described, and in succession thereafter the remaining pairs of relays of the first group 95 100 are energized and locked up. Upon the energization of relay 221, the stepping circuit, controlled by the stepping relay 204, instead of leading to the winding of relay 207, now leads by way of conductor 223, 105 right-hand armature and contact of the translating relay 214, armature and back contact of the number 9' counting relay 232 of the second group, winding of relay 233, contact 215 (6) to battery and ground. In 110 this manner the succeeding relays of the second group of counting relays are energized and locked up. Upon the energization of the final relay 234 of the second group, the stepping circuit is completed by way of conductor 235, front contact and left-hand armature of the translating relay 214, winding of relay 207 to battery and ground. The next deenergization of the stepping relay 204 permits the energization of relays 206 115 120 125 130

- and 208 which serve, as before explained, to advance the sender sequence switch 210 and to terminate the movement of the selective switch.
- 5 After the termination of conversation, the operator at the position shown is given a disconnecting signal in any well-known manner. She then operates the disconnect key 112, which closes a circuit for relay 105 including contact 111 (13). Relay 105 closes a circuit including upper left-hand contact 104 (13 to 17) for driving sequence switch 110 into position 18. In this position the down-drive power magnet 121 is energized by means of a circuit closed at contact 119. When the brush shaft reaches its home position, a circuit is closed from ground through brush 128, contact 132, conductor 133, contact 104 (18), winding of sequence switch 110 to battery and ground. Sequence switch 110 advances into its normal position and the circuit of magnet 121 is opened at contact 119. The apparatus is now restored to its normal condition.
- 15 25 What is claimed is:
1. In a controlling system, a selective switch, switch controlling mechanism comprising a plurality of relays arranged in two groups, means for operating in succession a variable number of the relays of the first group, means for operating in succession the relays of the second group, said groups being arranged such that a particular relay in each group is always the last relay operated in that group, and means responsive to the operation of said particular relays for determining the operation of said switch.
  2. In a controlling system, a selective switch, a switch controlling mechanism comprising a series of relays divided in two groups, means for operating in succession a variable number of the relays of the first group, means for operating in succession all the relays of the second group, said groups being arranged so that a particular relay in each group is always the last relay operated in that group, and means responsive to the operation of said particular relays for determining the operation of said switch.
  3. In a controlling system, a selective switch, a switch controlling mechanism comprising a series of relays divided in two groups, means for moving said switch, means controlled by the movement of said switch for operating in succession a variable number of the relays of the first group, means controlled by the movement of said switch for operating in succession the relays of the second group, said groups being arranged such that a particular relay in each group is always the last relay operated in that group, and means responsive to the operation of said particular relays for terminating the movement of said switch.
  4. In a controlling system, a selective switch, a switch controlling mechanism comprising a series of relays divided in two groups, the relays of the first group arranged to be successively operated in variable numbers thereof, the relays of the second group arranged to be successively operated, said groups being arranged so that a particular relay in each group is always the last relay operated in that group, means for operating either the relays of said first group, or the relays of said first group and the relays of said second group, and means responsive to the operation of said particular relays for determining the operation of said switch.
- 70 75 80 85 90 95 100 105 110 115 120 125 130
5. In a controlling system, a selective switch, a switch controlling mechanism comprising a series of relays divided in two groups, the relays of the first group arranged to be successively operated in variable numbers thereof, the relays of the second group arranged to be successively operated, said groups being so arranged that a particular relay in each group is always the last relay operated in that group, means for moving said switch, means controlled in the movement of the switch for operating either the relays of said first group or the relays of said first group and the relays of said second group dependent upon the extent of movement to be imparted to said switch, and means responsive to the operation of said particular relay in the first group when only the relays of said first groups are operated, for stopping said switch, said last means being also responsive to said particular relay of the second group when both the relays of the first and second groups are operated for stopping said switch.
6. In a controlling system, a selective switch, a switch controlling mechanism comprising a series of relays arranged in two groups, the relays of each group arranged to be operated in succession, said groups being so arranged that a particular relay in each group is always the last relay operated in that group, a plurality of keys, means controlled by the actuation of said keys for operating a variable number of the relays of the first group and for operating the relays of the second group, and means responsive to the operation of said particular relays for determining the operation of said switch.
7. In a controlling system, a selective switch, a switch controlling mechanism comprising a series of relays arranged in two groups, the relays of each group arranged to be operated in succession, said groups being arranged such that a particular relay in each group is always the relay last operated in that group, a plurality of keys, means controlled by the actuation of certain of said keys for operating a variable number of the relays of the first group, means controlled by the actuation of other of said keys for operating a variable number of the relays

of the first group and for operating the relays of the second group, means for moving said switch, and means responsive to the operation of one or the other of said particular 5 relays according to the key actuated for stopping said switch.

8. In a controlling system, a selective switch, a switch controlling mechanism comprising a series of relays divided in two 10 groups, the relays of each group arranged to be operated in succession, said groups being arranged such that a particular relay in each group is always the relay last operated in that group, a series of number keys, means 15 controlled by the actuation of keys representing certain numerals for operating corresponding numbers of the relays of the first group, means controlled by the actuation of keys representing other numerals for operating 20 the relays of the second group, means for moving said switch, and means responsive to the operation of said particular relays for stopping said switch.

9. In a controlling system, a selective 25 switch, a switch controlling mechanism comprising a series of relays divided in two groups, the relays of each group arranged to be operated in succession, said groups being arranged so that a particular relay in 30 each group is always the relay last operated in that group, a series of number keys, means controlled by the actuation of keys representing certain numerals for operating corresponding numbers of the relays of the first

group, means controlled by the actuation of 35 keys representing other numerals for operating corresponding numbers of the relays of the first group and for operating all the relays of the second group, means for moving said switch, and means responsive to the 40 operation of one or the other of said particular relays, depending on the key actuated, for stopping said switch.

10. In a controlling system, a selective switch, a switch controlling mechanism comprising a series of relays divided in two 45 groups, the relays of each group arranged to be operated in succession, said groups being arranged such that a particular relay in each group is always the relay last operated in 50 that group, a series of keys representing the consecutive numerals from 0 to 9, means controlled by the actuation of keys representing numerals less than five for operating corresponding numbers of the relays of the 55 first group, means controlled by the actuation of the remaining of said keys for operating corresponding numbers of the relays of the first group and for operating all the 60 relays of the second group, means for moving said switch, and means responsive to the operation of one or the other of said particular relays, depending on the key actuated, for stopping said switch.

In witness whereof, I hereunto subscribe 65 my name this 12th day of December A. D., 1919.

FRANKLIN A. STEARN.
